UNITED STATES PATENT OFFICE.

ALEXANDER STIRLING BURNETT, OF REDDISH, NEAR STOCKPORT, AND THOMAS COLLINS, OF LEVENS HULME, ENGLAND.

EMBOSSING AND LIKE MACHINE OR PRESS.

Application filed January 25, 1923. Serial No. 614,927.

To all whom it may concern:

Be it known that ALEXANDER STIRLING BURNETT and THOMAS COLLINS, both subjects of the King of Great Britain and Ireland, residing at Reddish, near Stockport, England, and Levenshulme, Manchester, England, respectively, have invented new and useful Improvements in or Relating to Embossing and like Machines or Presses, of 10 which the following is a specification.

This invention relates to machines primarily directed to embossing cardboard, mill board or the like, but which is applicable to printing or like purposes wherein a firm even 15 pressure is desired over a comparatively large area.

According to the invention the machine comprises a base formed with or having secured thereto side frames to carry a cross 20 member to receive the upward thrust. Slidably mounted on suitable guides is the platen or press-head to which downward movement is imparted by an inclined or cam member on a horizontally sliding member or members, hereinafter termed head presser-bars, 25 located between the platen and the head of the press, the cam or inclined surfaces being arranged to impart pressure evenly at a plurality of points over the area of the press 30 head, say at or near each corner, suitable anti-friction devices being interposed to minimize the friction.

The head presser-bars are preferably actuated by a vertically disposed cam pivotally mounted at the side of the machine and provided with manipulating means such as a handle or gearing according as the 35 machine is hand or power operated.

According to a further feature of the invention a travelling table is mounted on the base below the press-head which is actuated in synchronism with the before mentioned vertical cam so that the traverse takes place whilst the press-head is in the raised position and this can be conveniently effected by 40 a tappet lever adapted to engage a projection or projections pivotally mounted on the travelling bed during the return movement of the cam, said projection or projections 45 being swung on their pivots at the end of the forward movement and falling back into position behind said tappet lever so as to be engaged thereby and together with the 50 table moved with the cam during its return 55 movement.

When used for embossing, the embossing dies are secured to the table and according to a further feature of the invention said dies are formed with a projecting ledge at each end adapted to lie below clamping bars 60 held down by hook bolts engaging grooves in the edges of the table.

The invention will be more particularly described by the aid of the accompanying drawings, wherein:—

Fig: 1 is a side elevation of a press constructed according to the invention.

Fig: 2 is a front elevation, and

Fig: 3 a plan.

Fig: 4 is a detail view of the cam segment 70 and

Fig: 5 is a detail view of the type and securing strips detached.

Fig: 6 is a side elevation of a modified form of type clamping bar.

In carrying the invention into effect according to one convenient manner as illustrated and as adapted for use in embossing cardboard, mill board and the like to produce shop tickets, show-cards, etc., the improved press comprises a bed or base *a* having two vertical standards *b*, *b* at the side carrying a fixed cross-head *c* at the top. The latter is bored to receive, and constitute guideways for, two guide rods *d*, *d* secured 80 to the top side of the platen or press-head *e*, one near each corner. The press-head is provided with a series of anti-friction rollers *f*, say four, arranged in pairs in line with the guide rods *d* and the separate rollers of one pair being in line with the separate rollers of the other pair transversely of the machine to engage two presser-bars *g*, *g* provided with inclined surfaces *g*¹ or cams. 85

Around the projecting ends of the guide bars *d* are spiral springs *h* in compression and collars or nuts *d*¹ on the ends of the guide rods *d* so as to normally tend to raise the press-head *e* into contact with the presser-bars *g*. The rollers *f* are mounted in inclined runways *e*¹ formed on or secured to the presser head *e*, springs *f*¹ serving to normally keep said rollers at the bottom of the runways and additional rollers *i* mounted in runways *c*¹ formed on or secured to the underside of the press head *c* are provided to receive the upward thrust of the presser-bars *g*, *g*, spring *i*¹ being provided to normally retain the rollers at the left hand end of the runways.

The presser-bars g slide in guideways formed in the vertical standards b beyond which they project at one side. The projecting ends are connected to a cross-piece g^2 at a short distance from the end, and said projecting ends are formed with horizontal slideways to receive an adjustable cross-head j having a pendant arm j^1 adapted to form the vertical axis of an anti-friction roller k which is engaged by a cam segment l secured to a horizontal spindle m journaled in the bed a of the machine. The cam segment l is provided with a manipulating handle n . The shape of the cam g^1 on the presser-bars is preferably such as to give a quick raising and lowering movement but a slow pressure when in contact with the work and the cam segment l see Figure 4, is also shaped with a quick portion l^1 and slow pressure portion l^2 a return cam l^4 being attached to the rear end of the cam surface l^2 to return the roller k to the other side of the cam l , the surface l^3 ensuring a quick return movement of the presser-bars g . The cross-head j is adjusted by means of the nut o on the bolt o^1 to vary the pressure of the press-head e .

The base a is formed with a slideway a^1 to receive a travelling table p provided with a series of pendant arms q pivotally mounted so that they may swing inwards in one direction but form solid abutments in the other direction for a tappet lever arm r secured to the cam spindle m . The length of said lever arm r and the pitch of the pendant arms q is such that during the reverse movement of the segmental cam, the table p is moved forward through a distance equal to the width of the press-head to bring a fresh set of dies under said press head, the next succeeding pendant arm then having advanced for a sufficient distance to allow the tappet lever r to swing it upwards and pass beyond it as shown in dotted lines in Figure 1 at the next operation stroke of the pivotal cam l ready for a repeat traverse on the next backward movement of said cam, sufficient free or lost motion of the tappet arm being allowed to allow of the press-head being raised clear of the dies or type before the table is traversed. Attached to the cam segment l is a manipulating handle n by means of which said cam segment and tappet arm r are oscillated and an anti-friction roller s is mounted on the frame b to receive the side pressure on the cam segment.

The type or dies are formed to give the desired impression and assuming it is desired to emboss millboard with wording to constitute a show card said wording being covered by different coloured paper or ma-

terial to the background, the dies are outlined to a knife edge to press the covering paper into the millboard and cut the same out to the correct shape during the act of embossing. Said dies t see Figure 5 are formed with stepped edges so that they can be clamped on the table by suitable clamping bars u actuated by hook bolts v engaging slots or grooves w in the edges of the table p . Alternatively, bars u^1 of spring steel may be used, the ends of which are bent over to form spring grips to engage the edge of the work table. Said bars u^1 are provided with a layer of rubber or like friction material on the underside to engage the type and securely hold the same in position.

The details of the machine may be modified without departing from the spirit of the invention, for instance, the presser-bars may be actuated in both directions by a cam or cams the essential feature being the application of the pressure at a plurality of points over the press-head.

What we claim is:—

1. Presses for embossing cardboard, millboard or the like or for printing or like purposes comprising a frame on which is mounted a platen or press-head to which downward movement is imparted by inclined or cam-members on a horizontally sliding member or members, located between the platen and the head of the press, a cam or cams being provided to impart movement to the sliding member or members and the arrangement being such that the cams or inclined surfaces impart pressure evenly at a plurality of points over the area of the platen or press-head, substantially as described.

2. Presses for embossing, printing or the like as claimed in claim 1, characterized in that the horizontally sliding member or members is or are provided with an anti-friction roller adapted to be engaged by a cam-segment to traverse said sliding members, substantially as described.

3. Presses for embossing, printing and the like as claimed in claim 2, characterized in that the cam segment is interconnected with a tappet arm adapted to traverse the work table, substantially as described.

4. Presses for embossing, printing and the like as claimed in claim 1, characterized in that means are provided to clamp embossing dies on the work table, substantially as described.

In testimony whereof we have signed our names to this specification.

ALEXANDER STIRLING BURNETT.
THOMAS COLLINS.
